Primary Examiner — Kevin K Rudzinski*Assistant Examiner* — Evans David Delesline(74) *Attorney, Agent, or Firm* — Polsinelli PC(57) **CLAIM**

The ornamental design for a coin display neckpiece, as shown and described.

DESCRIPTION

FIG. 1 is a top, front and left perspective view of the coin display neckpiece showing our new design.

FIG. 2 is a rear perspective view thereof showing the neckpiece connector in a separated state.

FIG. 3 is a top plan view thereof.

FIG. 4 is a bottom plan view thereof.

FIG. 5 is a rear elevation view thereof showing the neckpiece connector in a connected state.

FIG. 6 is a front elevation view thereof.

FIG. 7 is a side view thereof.

FIG. 8 is another top plan view thereof having a coin secured within the display pendant; and,

FIG. 9 is a front perspective view thereof having the coin secured within the display pendant.

The coin shown in broken lines shows environment and forms no part of the claimed design.

1 Claim, 4 Drawing Sheets(56)
